UNITED STATES PATENT OFFICE.

GEORGE A. BOYER, OF LOS ANGELES, CALIFORNIA.

SPLASH OILING SYSTEM.

1,370,274.

Specification of Letters Patent.

Patented Mar. 1, 1921.

Application filed May 27, 1920. Serial No. 384,783.

To all whom it may concern:

Be it known that I, GEORGE A. BOYER, a citizen of the United States, residing at Los Angeles, in the county of Los Angeles and

5 State of California, have invented new and useful Improvements in Splash Oiling Systems, of which the following is a specification.

This invention is a splash oiling system 10 arranged to convey the lubricant splashed by a rotating member back to the casing of the machine of which the rotating member is a part. More specifically the invention is particularly applicable to an internal combustion engine wherein the lubricant in the 15 crank case is splashed by the fly wheel of the engine, the improved system contemplating the employment of means for conveying the lubricant splashed up by the fly 20 wheel back to the opposite end of the crank case of the engine.

It is the object of the invention to provide an improved system of this character 25 in which the means for collecting the lubricant splashed by the fly wheel is formed as an integral part of the usual engine frame construction, this lubricant collector being connected by a conduit with a usual port formed in the crank case of the engine, and 30 said conduit being, preferably, provided with a sight feed for indicating the proper working of the system.

The invention will be readily understood 35 from the following description of the accompanying drawings, in which—

Figure 1 is a perspective view of a portion of an engine frame showing the means for collecting the lubricant.

Fig. 2 is a side elevation, partly in vertical 40 section, of an internal combustion engine having the improved oiling system associated therewith.

Fig. 3 is a side elevation of the portion of 45 the engine frame embodying the lubricant collecting means.

Fig. 4 is a bottom plan view of the same, partly broken away.

The improved oiling system is employed 50 in connection with an internal combustion engine having the usual crank case 1, the rear continuation of which shown at 2 is arranged to receive the fly wheel 3 of the engine. The casing 2, as in the usual construction, is provided with a top closure plate 4 arranged adjacent to and in rear of the fly wheel 3. In my improved oiling sys-

tem this closure plate is provided at its under side with a lubricant collecting chamber arranged to receive the lubricant splashed by the fly wheel.

As an instance of this arrangement a chamber 5 is provided at the under side of plate 4, said chamber, preferably, extending lengthwise of said plate and gradually increasing in depth from a point 5^a toward 60 the end of said chamber which is adjacent the fly wheel. The portion of the chamber extending in the opposite direction along the plate 4 from the point 5^a is, preferably, of the same depth throughout to form the 65 reservoir 6. The forward end of chamber 5, preferably, turns at substantially right 70 angles to the longitudinally extending portion of said chamber as shown at 7, said turn in the lubricant collecting chamber being toward the direction of rotation of the fly wheel. This end portion of the collecting chamber is, preferably, arranged above 75 and in rear of the fly wheel, as clearly shown in Fig. 2, and the front end of said chamber 80 is open as shown at 8, and the side of said chamber adjacent fly wheel 3 is, preferably, 85 also open at the upper portion thereof as shown at 9. A screen 10 extends across the collecting chamber, preferably, at the junction of the angularly disposed end 7 and the longitudinally extending portion 5 of said chamber.

A pipe 11 communicates with the chamber 5, preferably, through a port 12 formed 90 in plate 4, this pipe extending laterally from the plate 4 as shown in Fig. 1. The port 12 is, preferably, arranged in the oil collecting chamber adjacent the junction of the reservoir 6 with the forward portion of 95 chamber 5 which is of gradually increasing depth. The pipe 11 is connected with a pipe 13 extending forwardly along the engine, preferably, adjacent the lower part thereof, and this pipe is shown as communicating with a sight feed chamber 14 which may be of any usual preferred construction. A pipe 15 leads from this sight feed chamber and said pipe communicates with the lower portion of the crank case 100 of the engine adjacent the forward end thereof. For this purpose one of the usual bolts received in a usual opening 16 at the bottom of the crank case for connecting the upper and lower portions of the crank case 110 may be removed and the pipe 15 may be threaded into this usual bolt opening.

In operation the oil splashed up by the fly wheel will be thrown by centrifugal force into the open end of the collecting chamber through both the open front end 5 of the angularly disposed portion 7 of said chamber and also over the wall 9^a at the side of said portion of the chamber which is adjacent the fly wheel and which terminates at its upper end in the opening 10. The oil thus collected in the portion 7 of the collecting chamber will flow therefrom into the main portion of the collecting chamber through the screen 10, the gradually reduced depth of the collecting 15 chamber bringing all of the lubricant thus collected at the enlarged end of the chamber toward the plate 4 so that it may be readily discharged from the collecting chamber through the port in plate 4 communicating with pipe 11. The reservoir 6 in rear of the discharge port 12 will be filled with the oil thus collected and will assist in maintaining a steady flow of oil from the collecting chamber into pipe 11 during operation of the system. The oil flowing into pipe 11 will be returned through the sight feed 14 where the condition of operation 20 of the system may be observed, and from thence the oil will be returned to the forward end of the crank case through the pipe 15.

Thus it will be seen that I have provided an efficient splash oiling system for an internal combustion engine in which the parts 25 are of few and simplified construction and the collecting chamber for the system made as a portion of a usual part of the crank case.

Various changes may be made without departing from the spirit of the invention as 30 claimed.

What is claimed is:

1. A splash oiling system for a casing having a fly wheel therein, said casing having a cover plate comprising a collecting 45 chamber upon the under side of said cover plate, said collecting chamber extending lengthwise of said plate and having its forward end angularly disposed relative thereto and projecting in the reverse direction 50 to the direction of rotation of the fly wheel, and a screen across said collecting chamber at the forward angularly disposed end thereof.

2. A splash oiling system for a casing 55 having a fly wheel therein, said casing having a cover plate comprising a collecting chamber upon the under side of said cover plate, said collecting chamber extending lengthwise of said plate and having its forward end angularly disposed relative thereto and projecting in the reverse direction to the direction of rotation of the fly wheel, said collecting chamber increasing in depth 60 toward said forward angularly disposed 65 end.

3. A splash oiling system for a casing having a fly wheel therein, said casing having a cover plate comprising a collecting 70 chamber upon the under side of said cover plate, said collecting chamber extending lengthwise of said plate and having its forward end angularly disposed relative thereto and projecting in the reverse direction 75 to the direction of rotation of the fly wheel, the end of said angularly disposed end of the collecting chamber and the side thereof adjacent said fly wheel being open.

In testimony whereof I have signed my name to this specification.

GEORGE A. BOYER.
